UNITED STATES PATENT OFFICE.

ELLISON L. BRAINARD, OF EAST HAMPTON, CONNECTICUT, ASSIGNOR TO
THE BARTON BELL COMPANY, OF SAME PLACE.

DESIGN FOR A SLEIGH-BELL.

SPECIFICATION forming part of Design No. 17,164, dated March 8, 1887.

Application filed February 7, 1887. Serial No. 226,871. Term of patent 7 years.

To all whom it may concern:

Be it known that I, ELLISON L. BRAINARD, of East Hampton, in the county of Middlesex and State of Connecticut, have invented and produced a new and original Design for Bells for Sleighs, &c., of which the following is a specification.

This design relates to the exterior shape and configuration of the bell, as shown in the accompanying drawing.

The top or crown of the bell is a dome, at *a*, extending down at the sides, with a reverse curve or ogee, as at *b*. The sides *c* are nearly straight, and the rim *d* is also nearly cylindrical, and the curve or cove *e* is between the parts *c d*. This configuration of bell is highly

ornamental and neat in appearance, especially where several are grouped together, as in a row of sleigh-bells.

I claim—
The design for a sleigh-bell having the shape or configuration shown, consisting in the design of the dome-shaped and ogee top, the nearly straight sides and rim, and the cove between the sides and rim, substantially as described and represented.

Signed by me this 12th day of January, 1887.

ELLISON L. BRAINARD.
